CARREL

Tom O. Gulliford, Rockford, and George W. Bicknell,
Marshall, Mich., assignors to The Worden Company,
Holland, Mich., a corporation of Michigan

Filed Jan. 12, 1968, Ser. No. 10,147

Term of patent 14 years

Int. Cl. D6—01

U.S. Cl. D33—7

FIG. 1.

FIG. 2.

FIG. 3.

FIG. 4.

FIG. 1 is a perspective view of the carrel;
FIG. 2 is a front elevation thereof;
FIG. 3 is a side elevation thereof; and
FIG. 4 is a plan view thereof.

The side opposite to that shown in FIG. 3 is identical to that shown in FIG. 3. The back is plain and unornamented.

We claim:

The ornamental design for a carrel, substantially as shown and described.
